UNITED STATES PATENT OFFICE

WILLIAM E. LUNDGREN, OF WORCESTER, MASSACHUSETTS, ASSIGNEE TO CROMPTON & KNOWLES LOOM WORKS, OF WORCESTER, MASSACHUSETTS, A CORPORATION OF MASSACHUSETTS

BOX MOTION FOR LOOMS

Application filed August 1, 1928, Serial No. 296,769.

This invention relates to a mechanism for raising and lowering the shuttle boxes in a drop box loom.

It is the general object of my invention to improve and simplify the construction of such box motions, reducing the number of parts and simplifying the manufacture and assembly thereof.

With this general object in view, important features of my invention relate to the provision of an improved give-way device; to the provision of improved devices for sliding the pinion starting teeth; to improved means for holding said pinions in predetermined angular positions, and to other details of construction which will be hereinafter described and more particularly pointed out in the appended claims.

A preferred form of the invention is shown in the drawings in which—

Fig. 1 is a side elevation of portions of a loom having my improved box motion mounted thereon;

Fig. 2 is an enlarged end view of the box motion, with certain parts broken away;

Fig. 3 is a sectional rear elevation, taken along the line 3—3 in Fig. 2;

Fig. 4 is a sectional front elevation, taken along the line 4—4 in Fig. 2;

Fig. 5 is a detail sectional view, taken along the line 5—5 in Fig. 4;

Fig. 6 is a side elevation of the give-way device; and

Fig. 7 is a detail sectional view, taken along the line 7—7 in Fig. 3.

Referring to the drawings, I have shown parts of a drop box loom including a loom frame 10, and drop boxes 11 mounted on a lifter rod 12 and slidable in a lower bearing 13, all of said parts being of the usual construction.

A lifter lever 14 is mounted on a floating pivot 15 and is connected by a link 16 to the lower end of the lifter rod 12. The weight 17 at the rear end of the lever 14 counterbalances the drop boxes 11 and lifter rod 12.

The lifter lever 14 is connected by a link 18 to a crankpin 19 (Fig. 2) on the rear pinion shaft 20. The floating pivot 15 is mounted on a lever 22 (Fig. 1) pivoted to the loom

side at 23 and connected by a link 24 to a crank-pin 25 on a front pinion shaft 26.

The construction for the front and rear pinions and their associated mechanisms is identical and a description of the rear pinion mechanism shown in Fig. 3 will apply equally to the construction of the front pinion mechanism.

Referring to Fig. 3, the pinion shaft 20 is rotatable in a bushing 30 in a bearing 31 forming an integral part of the box motion stand or frame F.

The stud 19 is fixed in the end of a crank arm formed in the shape of a cam 32 secured to the end of the shaft 20 by a taper pin 33 extending through the hub 34 of the cam 32.

The hub 34 is provided with flattened portions 35 (Fig. 7) at opposite sides thereof, which are normally engaged by a flat spring 36 mounted on a fixed support 37, said spring 36 being for a purpose to be described.

The usual intermittent or mutilated pinion gear 40 (Fig. 3) is fixed near the opposite end of the shaft 20, as by a pin 41. A grooved collar 42 is slidable adjacent the pinion 40 and constitutes means for sliding the starting teeth 44 (Fig. 2) of the pinion axially into and out of operative position.

The collar 42 is controlled by a yoke arm 45 mounted on the end of a stud 46 (Fig. 3) which is slidable in an elongated bearing portion 48 of the frame F. A spring 50 surrounds the reduced end of the stud 46 and is enclosed in the bearing so that it is entirely protected from dirt or injury. The spring 50 acts to yieldingly move the yoke 45 and collar 42 to the left, as indicated in Fig. 3.

Movement to the right is caused by a cord or flexible connection 54, connected to an offset arm 55 of the yoke 45 and conducted around guide pulleys 56 to suitable pattern mechanism, not shown.

When the pinion 40 is to be rendered operative, the collar 42 is permitted to slide to the left under the influence of the spring 50, causing the starting teeth 44 to be brought into position for engagement by the corresponding teeth of a driving gear 60 (Fig. 2) on the bottom or cam shaft 61 of the loom.

A stop motion plate 65 is mounted at the

side of each pinion 40 and engages a co-operating locking part 66 of the hub of the driving gear 60. The locking part 66 has a concentric portion 68 and recessed portions 69 and 70.

5 The stop motion plate 65 has concave end portions 72 adapted to receive the concentric portion 68 of the locking part 66, when the parts are positioned as shown in Fig. 5.

10 The flat spring 36 (Fig. 7) holds the pinions yieldingly in such position that the stop motion plate 65 is held, from turning, as the recess 69 passes under the corner of the plate. When one of the sliding teeth is moved to 15 operative position, however, the stop plate 65 will be positively rotated, and the corner of the plate 65 then swings into the recess 69 as in the well known Geneva stop motion.

10 It will thus be seen that I have provided a 20 positive stop motion which will absolutely prevent overrunning of the pinion gears at any speed of operation.

25 The recesses 74 for the stop motion plate 75 on the front pinion shaft 26 are similar to the recesses 69 and 70, but are formed in a different radial section, the plates 65 and 75 being out of alignment.

30 It is desirable to provide a give-way device in case the indicated motion of the drop boxes is prevented and it has been customary to provide an expensive yielding bearing construction for each of the pinion shafts 20 and 26. In my improved box motion, I mount the pinion shafts 20 and 26, as well as the cam 35 shaft 61 in fixed bearings in the frame F and provide a much simplified and improved give-way device for the main driving gear 60.

For this purpose I mount the gear 60 loose 40 on the bottom shaft 61 and provide the gear 60 with a locking arm 80 (Fig. 6) having a lug or projection 81 adapted to enter a notch 82 in a collar 83 fixed to the shaft 61.

A spring 85 connects the lever 80 to a stud 86 on the end of the driving gear, said spring 45 overlying in part a hub portion 87 projecting from the end of the gear 60. Under normal conditions, the lug 81 will be held firmly in the notch 82 and the driving gear will rotate with the cam shaft 61. If, however, 50 movement of the drop boxes or pinion shafts is prevented, the lug 81 will be forced out of the notch 82, thus freeing the cam shaft from the driving gear. As soon as the lug 81 moves out of the notch 82, it rests upon a concentric 55 surface of the collar 83 and offers very little resistance to continued turning of the bottom or cam shaft 61.

When it is desired to restore the driving 60 connection, the bottom shaft is turned until the lug 81 drops into the notch, and as the bottom shaft makes one revolution for each two picks of the loom, the driving gear is always restored in correct angular relation and proper timing, a feature not found with 65 the previous yielding box construction which

might re-engage the gears in any angular position.

It will be seen that I have provided a single and very simple give-way device in place of the two separate and expensive yielding 70 boxes previously described and that my improved construction embodies advantages not found in the previous box motions. When a pinion shaft bearing becomes worn, it can be easily repaired by first driving out the pin 75 33 and removing the crank cam 32. The shaft 20 is then removed, after which the bushing 30 may be forced out and a new bushing substituted.

Having thus described my invention and 80 the advantages thereof, I do not wish to be limited to the details herein disclosed, otherwise than as set forth in the claims, but what I claim is:—

1. In a box motion, a pinion gear, starting teeth therefor, and means to move said starting teeth axially, said means comprising a yoke arm, and a spring actuated plunger on which said yoke arm is mounted, said plunger being effective to give said arm a straight line 90 movement axially of said gear.

2. In a box motion, a mutilated pinion, an interrupted driving gear, Geneva stop motion devices associated with said pinion and gear to periodically hold said pinion from rotation for a portion of a revolution, and additional yielding means effective to hold said pinion from accidental rotation when said Geneva stop motion devices are ineffective to prevent such accidental rotation.

3. In a box motion, a mutilated pinion, an interrupted driving gear, Geneva stop motion devices associated with said pinion and gear to periodically hold said pinion from rotation for a portion of a revolution, said 105 pinion having a crank arm associated therewith having a hub with flattened peripheral portions, and a flat spring mounted in fixed position and yieldingly engaging said flat hub portions to hold said pinion from accidental angular movement when said Geneva stop motion devices are ineffective to prevent such accidental rotation.

In testimony whereof I have hereunto affixed my signature.

WILLIAM E. LUNDGREN.
